PILE PULLING DEVICE

Filed Sept. 28, 1927

UNITED STATES PATENT OFFICE.

ROBERT P. PETERSEN, OF PHILADELPHIA, PENNSYLVANIA, ASSIGNOR TO HENRY W. HORST COMPANY, OF PHILADELPHIA, PENNSYLVANIA, A CORPORATION OF ILLINOIS.

PILE-PULLING DEVICE.

Application filed September 28, 1927. Serial No. 222,442.

My invention relates to a new and useful pile pulling device, whereby piling which has been driven into the ground to a relatively great depth, may be expeditiously and 5 economically extricated or pulled out, without the exertion of excessive force or power.

When piling is driven deep into the ground, and more particularly when the planks or plates comprising such piling are provided 10 with interlocking edges, a "seal" is formed between said edges, due to the rust or dirt which accumulates over a long period of time and which cements or joins the same thus greatly increasing the difficulty of re- 15 moving or pulling out such piles, since, in addition to overcoming the resistance due to the frictional engagement of the pile with the ground, it is also necessary to break the lock or seal thus formed between the ad- 20 jacent contiguous piles, thereby greatly in- creasing the difficulty in pulling out or ex- tricating the piles and necessitating the em- ployment of additional force and power.

The object of my invention is to provide 25 a pile pulling device whereby the upward pull exerted on a pile being extricated is simultaneously translated into downward pressure exerted on the adjacent, contiguous pile, thereby breaking the seal or lock formed 30 between the contiguous, interlocking edges of said piles and facilitating the removal or pulling out of the same.

A further object of my invention is to 35 provide a pile pulling device which will be simple in construction but at the same time, efficient, light and durable, all of which characteristics are particularly essential in movable, or field equipment of this character.

To the above ends, my invention consists 40 of an auxiliary mast, adjustably carried by and interposed between the swinging boom of a derrick or other hoisting machine and the pile to be pulled out or extricated, upper and lower pulley blocks carried by said aux- 45 iliary mast and having operative relation with the reeling drums of said hoisting machine, the lower of said pulley blocks being adapted to be detachably secured to the pile to be pulled out, while the lower end 50 of said auxiliary mast is adapted to strad- dle and exert a downward pressure on the next adjacent pile.

My invention further consists of a novel construction in said auxiliary mast whereby

the upper and lower ends thereof are great- 55 ly strengthened and reinforced and whereby its adjustment and operation are greatly fa- cilitated.

My invention further consists in a novel manner of securing and collocating the hoist- 60 ing pulleys with relation to the hoisting ma- chine and the auxiliary mast to effect the object of my invention.

My invention further consists in various other novel features of construction here- 65 inafter described and claimed.

For the purpose of illustrating my invention I have shown in the accompanying drawings one form thereof which is at present preferred by me, since the same has been 70 found in practice to give satisfactory and reliable results, although it is to be under- stood that the various instrumentalities of which my invention consists can be variously arranged and organized and that my inven- 75 tion is not limited to the precise arrange- ment and organization of the instrumentalities as herein shown and described.

Referring to the accompanying drawings, Figure 1, represents a view in side eleva- 80 tion of a pile pulling device embodying my invention.

Figure 2, represents an end elevation of the same.

Figure 3, represents on an enlarged scale, 85 a view showing in details the construction of the lower portion of the mast seen in Figure 1.

Figure 4, represents a fragmentary plan view of the conventional piling to be pulled 90 out by the device embodying my invention.

Referring to the drawings, in which like reference characters indicate like parts, 1 designates the swinging boom of a hoisting machine, to the uppermost end of which is 95 secured the grooved wheel or pulley 2, over which passes the wire or other flexible hoisting cord 3 leading to the hoisting drums of a hoisting machine not shown. The front portion 4 of the wire 3 passes over the mov- 100 able pulley block 5 and stationary pulley block 6 and has its end secured to one or the other of said pulley blocks as at 7. 8 designates a second wheel or pulley over which passes the wire 9 which carries the auxiliary 105 mast 10 in an adjustable manner at any de- sired height above the ground. The mast 10 is provided at its lower end with the reinforce-

ing plate 15 and with the end angle irons 12 secured thereto by the bolts 13. A pair of centrally located juxtaposed, pendant angle irons 14 are secured to the bottom plate 15 and form therebetween an inverted U-shape seat which is adapted to straddle the piling 16 as will be seen from Figs. 1 and 3.

The upper end of the mast 10 is provided with the side reinforcing plates 17 secured thereto by the bolts 18. A spacing block 19 is employed on one side of the mast 10 and is held in place by the bolts 20, there being an upper reinforcing plate 21 common to the upper edge or surface of the mast 10 and the spacing block 19 as will be understood from Fig. 1. An inverted U-shaped bracket 22 is superimposed upon and encases the top of the mast 10 and the spacing block 19, and is secured in position by the common bolts 18 and 20 hereinbefore referred to. To the shorter side 23 of the bracket 22 is secured the bracket 24 which supports the pulley block 6, the spacing block 19 thus serving to maintain said pulley 6 in offset spaced relation with respect to the mast 10. The lower pulley block 5 is provided with the inverted U-shaped bracket 25 which is adapted to be secured to the pile 26 by the bolts 27, passing through the holes 28 and retained in position by the cotter pin 29 or by any other suitable means.

In Figure 4 I have shown a fragmentary plan view of the conventional piles 16 and 26, which are provided with the jaws 30 which interlock with each other when the piles are driven into the ground. Due to rust and dirt accumulating in and about the contacting jaws 30 the same are "sealed" or cemented together thus more firmly securing the piles to each other and greatly increasing the difficulty in extraction or pulling out of the piles.

The operation of the device is as follows:—

The pulley 5 is first secured to the pile 26 to be pulled out and the mast 10 is made to straddle the next adjacent pile 16 so that when an upward pull is exerted on the pulley 5 and pile 26, a corresponding downward pressure is exerted by the mast 10 on the adjacent contiguous pile 16, thus tending to break the seal or lock formed by the rust and dirt accumulating upon the joining or cementing the interlocking jaws 30 of the adjacent piles 16 and 26, and facilitating the pulling out of the pile 26.

When the pile 26 has been pulled out, the mast 10 is made to straddle the next adjacent pile 31 and the pulley 5 is now secured to the pile 16 which in turn is pulled out and so on. Thus the force exerted in pulling out one pile is simultaneously employed to facilitate the pulling out of the next succeeding, adjacent pile, without the exertion of any additional force or power.

The reinforcing plates 17 and 21 and the bracket 22 on the top of the mast 10 and the

reinforcing plates 15 and angle irons 12 on the lower end thereof, permit of the use of wooden mast 10 which will not break or be otherwise damaged by the excessive pressure to which it is subjected, thus combining the advantages of lightness and strength. By the collocation of the pulleys 5 and 6 with respect to the mast 10 and of the mast 10 with respect to the hoisting machine and the piling, I am enabled to employ the force developed by the hoisting machine to better advantage since the same force exerted upwardly on one pile is also exerted downwardly on the adjacent contiguous pile and thus facilitates the pulling out of said piles.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent is:

1. Means for pulling sheet piling, comprising a mast having a shoe adapted to straddle the top of the pile adjacent the pile to be pulled, upper and lower pulley blocks suspended on one side of said mast, and means to connect the lower block to the top of the pile to be pulled, said mast and blocks being adapted to be operatively connected to a crane or the like.

2. Means for pulling sheet piling, comprising a mast having means at its upper end to support a pulley block alongside of said end and means on its lower end to straddle the pile adjacent the one to be pulled, a second pulley block having means to attach it to the pile to be pulled, means to attach the top of said mast to a crane or the like, and a cable operatively connecting said pulley blocks to said crane.

3. Means for pulling sheet piling, comprising a mast having a shoe adapted to straddle the top of a pile, reinforcing side plates at the top of said mast, a spacing member secured to one side of the top, a U-shaped plate on the top of said mast embracing said spacing member, an upper pulley block suspended from one leg of said U-shaped plate below said spacing member, a lower pulley block adapted to be attached to the pile to be pulled, and a hoisting cable operatively connected to said pulley blocks.

4. Means for pulling sheet piling, comprising a mast having a shoe to fit over the top of a pile adjacent to the one to be pulled,

reinforcing side plates having lateral extensions on the upper end of said mast, a spacing member secured to the side of said upper end between said extensions, a reinforcing plate 5 on the top of the mast and having a downward extension enclosing said spacing member, a pulley block suspended from said down-

ward extension, a second pulley block suspended from the first block, and means on said second block to detachably connect it to 10 the pile to be pulled, said mast and blocks being adapted to be operatively connected to a hoisting machine.

ROBERT P. PETERSEN.
